UNITED STATES PATENT OFFICE.

FRANZ A. BOEDTCHER, OF BERGENFIELD, NEW JERSEY.

ILLUMINATED DIRECTIONAL SIGNAL FOR ELEVATORS.

Application filed February 20, 1922. Serial No. 537,740.

To all whom it may concern:

Be it known that I, FRANZ A. BOEDTCHER, a citizen of the United States, residing at Bergenfield, in the county of Bergen and State of New Jersey, have invented a certain new and useful Illuminated Directional Signal for Elevators, of which the following is a specification.

This invention is particularly directed to elevator signals adapted to be positioned at the various floors of a building to notify intended passengers of the direction of an approaching elevator car, so that after an intended passenger has pressed a floor button, he can readily observe the approach of the next elevator car and so partake of a position from which he can readily enter the car after the car has stopped at a floor and the floor door been opened.

Such elevator signals usually contain the words "up" or "down" and are associated with electric circuits controlled by the movements of the car, so that the signals light up automatically as the car approaches the respective floors.

It has been the practice in making signals of this character to stamp the words "up" or "down" from a plate of sheet metal, forming the front of a casing in which a lamp is positioned and in order to preclude the entrance of dust or dirt into the casing, the cut-out portions of the sheet metal plate are usually sealed by glass letters, which are cast and set in as inlays into the cut-out parts of the plate. With such constructions, the illumination of the interior of the casing will cause the letters to be lighted up and consequently they may be readily seen.

The construction specified however is open to many disadvantages. Aside from being expensive to manufacture, there is an ever present tendency of the glass letters falling out of the plate and this is particularly the case, when the plate is cleaned by a porter.

The object of the present invention is to provide a signal of the character described, which will not only be economical to manufacture, but will be more durable and in fact practically indestructible under all ordinary conditions.

In carrying out the present invention in its preferred practical form, I utilize a relatively thick plate or sheet of glass in one face of which is impressed the letter, letters or symbols which it is desired to embody in

the signal, and these letters or symbols which are in the form of depressions are preferably cast into the plate from one face thereof. The face of the plate from which the depression or depressions extend is preferably covered with a coating of some suitable substance to render that portion of the plate except the depressed portions thereof opaque, although instead of such a coating the said face of the plate may be frosted. This plate I employ has the front wall of a casing adapted to contain suitable illuminating means, such for example as an electric lamp. The lamp may be of any desired color if it is desired to have the signal appear colored, or the lamp may be of the conventional kind and the front plate may be backed up by a colored back plate in the form of a sheet of colored glass.

The front or recessed plate may have one or more letters or symbols depressed therein, but in any event, the lighting up of these symbols from the recessed side of the front plate will, by virtue of refracting qualities of the glass at the base of the recess give very brilliant lighting effects, which enables the signal to be read from any angle and imparts to the letters or symbols the effect of raised letters. It will be noted however that the exposed face of the front plate is continuous and uninterrupted and may be readily cleaned or polished up by a porter or attendant without fear of breakage.

Features of the invention, other than those specified, will be apparent from the hereinafter detailed description and claim, when read in conjunction with the accompanying drawings.

The accompanying drawings illustrate one practical embodiment of the invention, but the construction shown therein is to be understood as illustrative only, and not as defining the limits of the invention.

Figure 1 shows a signal with an associated illuminating lamp in perspective.

Figure 2 is a sectional perspective taken on the line 2-2 of Figure 1; and,

Figure 3 is a view similar to Figure 2, but showing the parts dissociated with respect to one another.

While the present invention may differ in details of construction or in letters or in symbols from the showing in the accompanying drawings, I have illustrated an "up" signal embodying the letters "u" and "p" for the purpose of illustration.

Moreover, each of these letters is shown as a separate unit, two units being associated with one another to produce the complete signal.

5 The invention comprises a sheet or plate of glass 1 which in the preferred form of the invention constitutes a front plate. This plate has molded in the back thereof a depression or recess 2, which is in the form 10 of a symbol, letter or other character, such for example as the letter "u."

The side walls of the depression preferably converge toward the base of the depression, though this while preferred is not 15 essential. The back or recessed face of the front plate 1 is rendered opaque in any suitable manner, and this can be conveniently accomplished by applying a coating of some suitable opaque substance as shown at 20 3 in Figure 3.

The front plate 1 is preferably, though not essentially, backed up by a back plate 4, which is preferably of transparent glass, though frosted glass may be used for this 25 purpose if desired.

In practice, the front plate 1 and the back plate 4 constitute an element back of which is adapted to be positioned a lamp 5. The said element may be one of a group of elements formed in substantially the same manner as described and may constitute the front wall of a casing in which the lamp 5 is positioned so that the lamp 5 when illuminated will illuminate the depressions 2. If 30 it is desired that the letters show up in color, the back plate 4 may be colored and any form of incandescent light 5 employed. On the other hand, the back plate 4 may be 35 colorless and a colored lamp 5 may be employed.

40 In grouping a plurality of front plates 1 embodying different letters or symbols associated with one another to make up the desired signal, a back plate 4 may be used for 45 each front plate 1 or a single back plate of sufficient size to cover the back of all the assembled front plates may be employed. Moreover, the front plate may be made sufficiently large to carry a plurality of letters, 50 symbols or the like and thus obviate the necessity of grouping a plurality of front plates together to make up the desired sign.

In the preferred manner of carrying out the present invention, the plate 1 constitutes the front plate and the lamp is positioned rearwardly of the back plate 4. This assembly is recommended for the reason 55 that the light from the lamp 5 in passing

through that portion of the plate 1 at the base of the depression is subject to the refractive qualities of the glass from which the front plate 1 is formed and if the sides of the depression converge toward the base thereof, the refracting qualities will cause the letters or symbols to stand out in sharp contrast to the remainder of the plate, so that they will appear as raised letters or symbols of unusual brilliancy and can be seen from practically any angle. I may however in employing the signal of this invention, reverse the position of the parts, and utilize the plate 1 as a back plate and the plate 4 as a front plate. In this construction, the letters will appear sunken or in relief.

When the plate 1 is employed as a front plate, a smooth uninterrupted surface is presented which may be cleaned without fear of breakage or the dislodging of the letters as has been the case in prior constructions. 80 The present invention after being initially set up or assembled will last practically forever and is not dependent for its use upon adhesives or cements for holding the parts in assembled relation.

85 The signal of the present invention is economical to manufacture, easily cleaned, more brilliant in its lighting effects and more durable than prior constructions. While particularly adapted for use in the 90 elevator arts as a signal, it is adapted for general use and the structure shown in the drawings may be changed in details as by the substitution of equivalents without departing from the invention, which is to be 95 understood as broadly novel as is commensurate with the appended claim.

Having thus fully described the invention, what I claim as new and desire to secure by Letters Patent is:

100 An illuminated signal for elevators embodying a plate of glass one face of which is provided with a depression in the form of a character or symbol, the undepressed portion of said face being opaque, a source of light positioned adjacent the opaque face of the plate and adapted to illuminate the depression in said face so that said depression will appear from the opposite face of the plate as illuminated, and a color screen positioned between the base of the depression and the source of light.

110 In testimony whereof I have signed the foregoing specification.

FRANZ A. BOEDTCHER.
